(57) **CLAIM**

The ornamental design for a storage bag, as shown and described.

DESCRIPTION

FIG. 1 is a front, left, and top perspective view of a storage bag showing my new design;
FIG. 2 is a rear, right, and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is a partial enlarged view taken from 9 in FIG. 2. The broken lines in the drawings depict portions of the storage bag that form no part of the claimed design. The dot-dash broken lines depict areas of enlargement and form no part of the claimed design.
